ARTHUR JAMES TIZLEY, OF NEW YORK, N. Y., ASSIGNOR TO E. F. CALDWELL & CO.,
OF NEW YORK, N. Y.

OPERATING MEANS FOR ELECTRIC-LAMP SWITCHES.

1,108,641.

Specification of Letters Patent. Patented Aug. 25, 1914.

Application filed May 25, 1914. Serial No. 840,780.

To all whom it may concern:

Be it known that I, ARTHUR J. TIZLEY, a subject of the King of Great Britain, and a resident of the city of New York, borough 5 of Brooklyn, in the county of Kings and State of New York, have invented a new and Improved Operating Means for Electric-Lamp Switches, of which the following is a full, clear, and exact description.

10 My invention relates to a means for operating electric lamp switches, and it has for its object to provide a rotary lamp switch member with a stud movable in a slot in a casing by a cam mounted on a collar so that 15 the switch member may be rotated a distance by the collar and the cam, and with a further rotary movement of the collar the cam may push the stud into a recess at the slot which permits the cam to pass the stud. 20 The switch member may then be moved back to normal position by a spring provided for this purpose. The rotary switch member having the stud may be connected with an electric switch of a well-known type. 25 Additional objects of the invention will appear in the following specification in which the preferred form of my invention is disclosed.

In the drawings similar reference characters refer to similar parts in all the views in which—

Figure 1 is a side elevation of a lamp provided with my improvement; Fig. 2 is an enlarged sectional view showing my improvement means for operating the electric lamp switch; Fig. 3 is a sectional view on the line 3—3 of Fig. 2; and Fig. 4 is an enlarged view showing the switch within the casing.

By referring to the drawings it will be seen that a casing 5 is provided which encloses a switch of a type having a conductor 6 which leads to the lamp 7 and a second conductor with which the switch is connected. The switch is constructed with an insulating member 8 rotatably mounted on the conductor 6, a conducting member 9 being secured to one side of the insulating member 8, this conducting member 9 having portions bent over the periphery of the insulating member 8 at 10 and 11. It will be seen that the insulating member 8 is ratchet shaped, and that it is engaged by a spring 12 so that with the rotary movement of the insulating member 8, the conducting member 12 may be brought

into contact with the conducting member 9 at 10 or 11 and that with another movement of the insulating member 8, the conducting member 12 will be brought into contact with a surface of the insulating member 8 to open 60 the switch. This is all of a wellknown construction in which the member 9 is connected with the conducting member 13 to which a binding post 14 is secured. The conducting member 9 is secured to one side 65 of the insulating ratchet member 8. At the other side of the insulating ratchet member 8, there is secured a plate 15 with ratchet teeth which are engaged by the ratchet plate 16, the ratchet plate 16 being held yieldingly 70 in engagement with the ratchet plate 15 by the spring 17, this spring 17 having an extending terminal 18 secured to the arm 19 mounted on the plate 16, this arm 19 serving to carry the stud 20 which is movably 75 disposed in a slot 21 in the casing 5. This slot 21 has a recess 22 adjacent its end 23. It will be understood that by moving the stud 20 the plate 16 will be rotated and with it the plate 15 carrying the insulating member 8, leaving the insulating ratchet member 8 to bring the conducting member 12 into engagement with the periphery of the insulating member 8 or with the conducting member 9 at 10 or 11, as may be desired, the 85 switch being operated in this manner.

As a means for moving the stud 20 I provide a collar 24 which is rotatably mounted on the casing 5 as shown in the drawings, this collar 24 having cams 25 which are 90 adapted to engage the stud 20 and move it in the slot 21 to the recess 22. When the stud 20 reaches the end 23 of the slot 21, it is pushed into the recess 22 by one of the cams, the cam and the collar 24 being permitted 95 in this manner to continue the rotary movement while the stud 20 with the arm 19 and the plate 16, are rotated by means of the spring 17 to obtain a new engagement with the ratchet teeth on the plate 15 to move 100 again the insulating member 8 when the collar 24 is rotated to bring one of the cams 25 into engagement with the stud 20.

Having thus described my invention I claim as new and desire to secure by Letters 105 Patent:

1. In a means for operating an electric lamp switch, a rotary member having a stud, a casing having a slot in which the stud is movably disposed, there being a recess in the 110

casing at one side and adjacent an end of the slot, a collar for rotating relatively to the casing and provided with a cam for moving the stud in the slot, and from the slot 5 into the recess, means for returning the rotary member and the stud to a normal position, and switch means operable by the rotary member.

2. In a means for operating an electric 10 lamp switch, a rotary member having a stud, a casing having a slot in which the stud is movably disposed, a cam for moving the stud in the slot, means for operating the cam, means for returning the rotary member 15 and the stud to a normal position, and switch means operable by the rotary member.

3. In a means for operating an electric lamp switch, a rotary member having a stud, a collar rotatably mounted and having a cam for engaging and moving the stud, means for returning the rotary member and the stud to a normal position after the termination of said movement by the cam, and switch means operable by the rotary member. 20 25

In testimony whereof I have hereunto signed my name to this specification in the presence of the two subscribing witnesses.

ARTHUR JAMES TIZLEY.
